UNITED STATES PATENT OFFICE

161,890

HANDLE

Domenick Acocello, Los Angeles, Calif.

Application April 13, 1950, Serial No. 9,188

Term of patent 14 years

(Cl. D10—8)

To all whom it may concern:

Be it known that I, Domenick Acocello, a citizen of the United States, residing in the city and county of Los Angeles, and State of California, have invented a new, original, and ornamental Design for a Handle, of which the following is a specification, reference being had to the accompanying drawing forming part thereof.

Fig. 1 is a perspective view of a handle, showing my new design.

Fig. 2 is a side elevation showing the handle on a smaller scale as viewed from the left in Fig. 1.

Fig. 3 is a front elevation thereof.

Figs. 4 and 5 are respectively top and bottom end elevations of the handle shown in Fig. 3.

Fig. 6 is a section on line 6—6 of Fig. 3.

I claim:

The ornamental design for a handle, as shown.

DOMENICK ACOCELLO.
